Attorney

UNITED STATES PATENT OFFICE.

JAMES ALEXANDER MOORE, OF WEIR, KANSAS, ASSIGNOR OF ONE-HALF TO GUSTAVE F. PHILLIPPAR, OF WEIR, KANSAS.

CRUTCH.

Application filed September 28, 1921. Serial No. 503,707.

To all whom it may concern:

Be it known that I, JAMES A. MOORE, a citizen of the United States, residing at Weir, in the county of Cherokee and State 5 of Kansas, have invented new and useful Improvements in Crutches, of which the following is a specification.

This invention relates to crutches, and particularly to cushioning devices for absorbing the shock incident to the use of the 10 crutch.

The primary object of the invention is to provide a crutch of simplified and improved construction, wherein the shocks and jolts 15 to which the crutch is necessarily subjected in use will be absorbed by improved mechanism carried by the crutch and will not be delivered to the shoulder and arm of the user of the crutch.

20 A further object of the invention is to provide a crutch of the character stated wherein the cushioning mechanism is of simple construction and composed of but few parts, the said parts being constructed and 25 arranged in such manner as to adapt themselves readily to the ordinary crutch now in use, which can not become readily broken, impaired or deranged, and which will prove thoroughly practical and efficient in use.

30 A still further object of the invention is to provide a crutch of such nature as to afford a decided cushioning effect to prevent transmission of shocks or jars to the user, and which when not subjected to pressure will assume normal or extended position.

With these and other objects in view, the invention consists of the features of construction, combination and arrangement of 40 parts, hereinafter fully described and claimed, reference being had to the accompanying drawing, in which:—

Figure 1 is a fragmentary side elevation of a crutch constructed in accordance with 45 the invention.

Figure 2 is a similar view, parts broken away, and illustrating more in detail the manner in which the cushioning mechanism is assembled with the crutch,

50 Figure 3 is a transverse sectional view

taken substantially upon line 3—3 of Figure 1, and

Figure 4 is a similar view taken upon line 4—4 of Figure 1.

Referring now more particularly to the 55 drawing, the longitudinal rails or bars of the crutch are indicated at 5, and these rails are spaced relatively far apart at their upper ends, being connected by the fixed head 6, and it is understood that they converge at 60 their lower or ground engaging ends.

The head 6 may be secured to the spaced upper ends of rails 5 in any approved or desired manner, screws 7 being employed in the present instance, such screws affording a rigid connection between the said head and the rails. The shoulder piece or rest is indicated at 8, and is of such shape and size as to comfortably fit in the arm pit of the user of the crutch, and this shoulder piece 70 is connected to the crutch body in such manner as to move relative thereto. This relative movement is for the purpose of absorbing the shock incident to the use of the crutch, and a shock absorber such as a spring 75 9 is interposed between the shoulder piece and the head 6. In order to absorb shocks which might be delivered to the arm of the crutch user through the hand piece 9', the latter is connected positively to a traveller 80 10, the latter in turn being connected to the resiliently supported shoulder piece 8.

More particularly, the shoulder piece 8 has depending therefrom at its middle point a rod or stem 11. This rod or stem 11 is 85 threaded at its upper end to receive a round nut 12. The shoulder piece is formed with a T-shaped opening composed of the vertical portion 13 and the horizontal transverse portion 13^a. The portion 13 opens at its lower 90 end through the base of the shoulder piece 8 and at its upper end intersects the portion 13^a. The portion of the rod 11 immediately below the said threaded upper end to which the nut 12 is attached occupies the opening 95 13 and forms a journal or axis on which the shoulder piece 8 is pivotally supported. The nut 12 lies between the top and bottom walls of the opening 13^a, and thus acts to hold the shoulder piece from upward or 100

- downward displacement, but permits said shoulder piece to have lateral pivotal or rotative movement on said portion of the rod which forms a journal or axis therefor. As shown, the opening 13 is disposed in vertical alinement with a vertical opening 13^b formed centrally in the head 6. The rod or stem 11 extends downward loosely through this opening 13^b and through an opening in 10 the upper guide member or traveler 10 and is threaded at its lower end to receive jamb nuts 14, whereby said rod or stem is fixed to said guide member or traveler 10. This guide member 10 fits loosely between the 15 side rails 5, and is yoked at its ends as shown in Figure 4 to loosely embrace the said rails. The hand grip or piece 9' is provided near its ends with openings 15 to loosely receive the side rails 5, as shown in Figure 3, and 20 the hand piece 9' is rigidly connected with the upper traveller 10 by means of the rods 16. These rods are connected to the traveler and hand piece by means of the jamb nuts 17, as shown.
- 25 The expansion spring 9 is in the form of a coiled spring as shown, the same encircling the stem 11 between the shoulder piece 8 and head 6, and bearing at its ends against bearing plates or washers 18.
- 30 By constructing the crutch in the manner set forth, it is apparent that the shocks transmitted to the crutch when in use will be absorbed by the cushioning spring 9, so that such shocks will not be delivered to the 35 shoulder of the user or to the hand and arm through the hand grip 9'. The spring 9 shall be of such strength as not to give or collapse too freely, so that the supporting effect of the crutch will not be overcome. It 40 will be understood, of course, that in the event of the spring 9 becoming impaired, it may be readily removed and replaced, and it will be further understood that springs of the desired tensile strength will be applied 45 to the stem 11 in accordance with the desires of the user of the crutch and depending upon the weight of the person for whose use the crutch is intended.
- 50 As the crutch is used, upon being applied to the ground, the weight of its user is thrown partly upon the shoulder piece 8 and partly upon the hand grip 9'. By reason of the fact that these two main supporting or weight receiving elements are rigidly connected, they will both give at one time and the weight will be assumed by the expansion 55 spring 9, whereby the shock incident to the application of the crutch to the ground in walking will be absorbed.
- 60 Also, it will be observed, as the shoulder piece 8 is mounted to turn or rotate on the rod or stem 11, lateral motion of the shoulder piece is permitted relative to the crutch body, this movement enabling the crutch to 65 adapt itself to peculiar twists which are fre-

quently given to crutches in the walking operation.

With the crutch constructed and assembled in the manner stated, it is apparent that the objects set forth will be fully attained, and that fatigue and exhaustion frequently experienced by those having to use supporting crutches will be greatly minimized or wholly removed.

The foregoing is a description of the invention in its preferred embodiment, however, it is obvious that variations in the construction of the mechanism, the assemblage and coordination of the parts thereof may be resorted to if desired without departing from the invention as defined by the claims.

Having thus fully described my invention, I claim:

1. In a crutch, a traveling hand piece, a movable shoulder piece, means connecting said hand and shoulder pieces for vertical movement in unison, and resilient means acting on one of said pieces for normally maintaining both of said pieces at the limit of its movement in one direction.

2. In a crutch, the combination with the side rails and the head thereof, of a traveling hand grip carried by said rails, a shoulder piece movable toward and from said head, a connection between said shoulder piece and said hand grip, and means resiliently supporting said hand grip.

3. In a crutch, the combination with the side rails and head thereof, of a hand piece movable upon said side rails, a traveler movable upon said rails, a connection between said traveler and said hand piece, a shoulder piece resiliently supported by said head, and a connection between said shoulder piece and said traveler.

4. In a crutch, the combination with the side rails and head thereof, of a hand piece movably mounted between said side rails, a traveler movable between said rails, a connection between said hand piece and said traveler, a shoulder piece yieldably supported by said head, and a connection between said traveler and said shoulder piece.

5. In a crutch, the combination with the side rails and the head thereof, of a hand piece slidably engaging said side rails, a shoulder piece resiliently supported by said head, and a connection between said shoulder piece and said hand piece, said shoulder piece being rotatably mounted on said connection.

6. In a crutch, the combination with the side rails and the head thereof, of a hand grip, the said hand grip having spaced openings therein to receive said side rails, a traveler interposed between said side rails and spaced from said hand grip, the ends of said traveler being yoked to embrace said side rails, rods rigidly connecting said hand grip and said traveler, a stem rigidly con-

nected to said traveler at its lower end and extending loosely through and slidably supported by said head, a shoulder piece rotatably supported by the outer end of said stem, 5 and an expansion spring encircling said stem and interposed between said shoulder piece and said head.

In testimony whereof I affix my signature in presence of two witnesses.

JAMES ALEXANDER MOORE.
